UNITED STATES PATENT OFFICE

CARL ALBERT, OF ZOBLITZ, IN ERZGEBIRGE, GERMANY

KITCHEN RANGE WITH GRID IRON FOR CHILDREN

Application filed August 16, 1927, Serial No. 213,419, and in Germany December 11, 1926.

This invention relates to a kitchen range with gridiron for children.

Spirit-burners in which perforated sheet metal plates are arranged above the burner 5 have become known for other purposes. Such burners can however not be used as grid irons for roasting in kitchen-ranges for children as the flame is not low enough and not distributed sufficiently uniformly.

10 According to the invention bars standing on edge are arranged above the plate of perforated sheet metal. The plate of perforated sheet metal does not let pass the points of the flames through between the grate-bars and the 15 flames are distributed by these bars so that the grate can be used in connection with kitchen-ranges for children.

A kitchen-range for children according to the invention is shown, by way of example, in 20 the accompanying drawing in

Fig. 1 in front elevation and in

Fig. 2 in top plan view.

Over a spirit burner 1 a grid iron is arranged which consists of a metal frame 2 in 25 the lower end of which a plate 3 of sieve-like perforated sheet metal is stretched. Longitudinal bars 4 standing on edge are arranged above the perforated plate 3 in the frame 2 and spaced 10 mms. The grate-bars 4 do not 30 rest on the perforated plate 3, but about 1 mm. above the same (Fig. 1) so that the flames are uniformly distributed. The grate bars 4 are inserted in vertical slots in the corresponding arms of the downwardly directed 35 flange of the metal frame 2. A grid-iron of this type can be used only in kitchen-ranges for children as it is of small size and completely enclosed.

I claim:

40 A kitchen-range for children comprising in combination with a spirit burner, a frame above said burner, a sieve-like perforated plate fixed in said frame, grate-bars standing on edge mounted in said frame at a short distance above said perforated plate so that a 45 grid-iron is formed to obtain a low and uniformly distributed flame.

In testimony whereof I affix my signature.
CARL ALBERT.
